CLAIM

The ornamental design for a comestible package, as shown and described.

DESCRIPTION

FIG. 1 is a perspective view of a comestible package, showing our new design;

FIG. 2 is a front view of the embodiment shown in FIG. 1; FIG. 3 is a rear view of the embodiment shown in FIG. 1; FIG. 4 is a side view of the embodiment shown in FIG. 1; FIG. 5 is another side view of the embodiment shown in FIG. 1;

FIG. 6 is a top view of the embodiment shown in FIG. 1; FIG. 7 is a bottom view of the embodiment shown in FIG. 1; and,

FIG. 8 is another perspective view of the embodiment shown in FIG. 1, as shown in an alternate configuration.

The broken lines of a relatively lesser weight form no part of the claimed design. The dashed lines of a relatively greater weight represent perforations. The broken lines of a relatively lesser weight form no part of the claimed design. The broken lines of a relatively greater weight represent perforations and form part of the claimed design.

1 Claim, 8 Drawing Sheets
